[57] **CLAIM**

The ornamental design for a muffin holder, as shown and described.

DESCRIPTION

FIG. 1 is a perspective view of a muffin holder showing our new design;

FIG. 2 is a side elevational view thereof;

FIG. 3 is a top plan view thereof;

FIG. 4 is a bottom plan view thereof;

FIG. 5 is a perspective view of a second embodiment thereof;

FIG. 6 is a side elevational view thereof;

FIG. 7 is a top plan view thereof; and,

FIG. 8 is a bottom plan view thereof.

The oven shown in broken lines in FIGS. 1 and 5 is shown for illustrative purposes only and forms no part of the claimed design.

FIG. 1**FIG. 2****FIG. 3****FIG. 4****FIG. 5****FIG. 6****FIG. 7****FIG. 8**
